COLLAPSIBLE BUILDING DRUM

Hollis C. Hodgkins, Eau Claire, Wis., assignor to
United States Rubber Company, New York,
N. Y., a corporation of New Jersey

Application February 25, 1950, Serial No. 146,312

14 Claims. (Cl. 154--9)

1

The present invention relates to a building drum for use in building tire casings, belt carcasses, vessels, or other articles of fabric and rubber commonly assembled in generally band form. More particularly it relates to a rotatable building drum of the type which may be collapsed to permit easy removal of the completed article.

It is an object of the invention to provide a new and improved building drum of the collapsible type which is of rugged yet simplified construction and in which wear of the parts does not adversely affect an accurate collapsing and expanding action of the drum.

Another object of the invention is the provision of a collapsible building drum so constructed and arranged that the operating linkage for expanding and collapsing the drum is not adversely affected by centrifugal forces developed as the drum rotates.

Another object is the provision of a collapsible drum that can be attached to and detached from a tire building machine shaft with ease and accuracy but without undue wear or strain on the attaching means.

Still another object of the invention is to provide a collapsible building drum in which the collapsing parts are symmetrically arranged about the axis of the drum thereby providing for interchangeability of the parts of the drum and the collapsing mechanism.

A further object of the invention is to provide an improved collapsible building drum which may be adjusted to build articles of a range of sizes and shapes and in which the necessary adjustments may be easily and quickly made.

Still a further object is the provision of an improved building drum which can be collapsed and expanded rapidly without subjecting the parts to shock.

These and other objects and advantages will appear more fully in the following detailed description when considered in connection with the accompanying drawings, in which:

Fig. 1 is a sectional view, taken substantially along the lines 1—1 of Fig. 2, of a building drum embodying the features of the present invention, certain parts being broken away to reveal the structure in more detail;

Fig. 2 is an end view of the drum with parts broken away;

Fig. 3 is a side view of the drum, taken partly in section, substantially along the lines 3—3 of Fig. 4, in the collapsed condition;

Fig. 4 is an end view of the drum in the collapsed condition;

2

Figs. 5 and 6 are perspective views of parts of the mechanism for controlling the collapse of the drum; and

Fig. 7 is a fragmentary sectional view of an edge portion of the drum illustrating a means for changing the width of the building surface of the drum.

Referring to the drawings, and particularly to Fig. 2, the rotatable tire building drum shown therein comprises a series of smaller or minor arcuate sections, or key segments 10, 11 and 12, and a series of larger or major arcuate sections or segments 13, 14 and 15 alternately disposed with respect to said key segments, and forming therewith a smooth contiguous cylindrical building surface when the drum is in the expanded condition.

The entire drum structure is supported from a central hub member 16 (Figs. 1 and 3) having, as shown in greatest detail in Fig. 1, a section 17 of reduced diameter, wherein the means for actuating the drum, such as a pneumatic cylinder 18, is preferably located. The key segments 10, 11 and 12 are supported in part from a collar 19 which is fixed by a set screw 20 to the reduced portion 17 of the hub 16. The collar 19 has keyways 21 (Fig. 5) whereby it is keyed to the hub to prevent it from rotating relative thereto.

For the purpose of attaching the smaller or key segments 10, 11 and 12 to the fixed collar 19 in a radially movable manner, collapsible toggle links 25 and 26 are provided in association with each of said segments. A lug 27 (Figs. 1 and 5) extending from the collar 19 is engaged by the inner end of link 25 and is pivotally secured thereto by a pin 28 (Fig. 1) passing through a hole 29 (Fig. 5) in the lug. A screw 30 (Fig. 1) passing through the lug 27 permits tightening of the pivot pin 28 by squeezing together the walls of a slot 31 (Fig. 5) provided in the lug for this purpose. The link 26 is attached to a lug 32 on the inner surface of segment 11 by a pivot pin 33 in a similar manner.

Forked ends of links 25 and 26 intermediate the hub and segment are both joined by a similar pivot pin 35 to an actuating toggle arm 36 extending generally axially of the drum. This toggle arm 36 is, in turn, pivotally joined in like manner to radially extending lugs 37 on an axially movable actuating plate 38. It will be understood that each of the other two key segments 10 and 12 are attached to the actuating plate 38 and to the hub collar 19 by a pivotal link and toggle arm arrangement identical to that just described in association with key seg-

ment 11. It should also be noted that for larger size drums, I may provide more than one such pair of links 25 and 26 for each key segment, the better to support and collapse the segments.

Considering now the structure by which the larger segments, 13, 14 and 15 are collapsibly supported from the hub of the drum, there is provided, in association with the fixed hub collar 19, a rotatable collar 40 having generally radially extending arms 41. This spider-like member, as shown in Fig. 6, has a central aperture 42 through which the hub portion 17 extends, and is equipped on one face with axially projecting lugs or stop members 43, designed to ride in arcuate slot-like guideways 44 (Fig. 5) formed in each end face of the fixed hub collar 19 by axially extending projections or stops 45 thereon. In this way, spider member 40 is capable of limited rotation with respect to the hub of the drum.

As is shown in Fig. 1, one such rotatable spider 40 engages one end of the fixed collar 19, while another such rotatable collar or spider 46, of identical construction, but facing in the opposite direction, engages the other end of collar 19. A cylinder head member 47 on the end of the actuating cylinder 18, and a flange portion 48 extending from the hub, maintain the spiders 40 and 46, respectively, in place on the hub. The spiders are therefore unable to move axially of the drum. Spider 46 also has generally radially extending arms 49, similar to the arms 41 of spider 40, but the arms 49 are canted in the opposite direction with respect to arms 41, as appears most clearly in Fig. 2, by reason of the fact that the two spiders are oppositely disposed in assembly.

Each arm 41 of the spider 40 is pivotally joined or fulcrumed to a yoke-like connecting fork, or control link 53, which serves pivotally to connect the key drum segments to the larger drum segments in such a manner as to transmit the desired collapsing movement from the key segments to the larger segments, as will be described later. The yoke or control link 53 fits into the forked end 54 of arm 41 and is joined thereto by a fulcrum pin 55 passing through holes 56 in the fork 54 and hole 57 in the yoke 53 (Fig. 1) whereby the forks are enabled to swing or pivot generally radially of the drum in a plane transverse to the axis of the drum. A set screw 58 threaded into the arm 41 permits tightening of the pivot pin in place in the usual manner. Bushings 59 of suitable bearing material are provided in the holes 56 as shown for smooth operation of the pivotal joints.

One fork or arm 61 of the control yoke 53 is pivotally attached to projecting lugs 62 on the inner surface of a larger segment 13, by means of a pivot pin 63 passing through holes 64 in the lugs and hole 65 in the arm 61. The usual set screw 66 and bushings 67 of bearing metal are provided. The other fork or arm 68 (Fig. 2) of the yoke 53 is pivotally connected to a key segment 10 through a short auxiliary tie link 70. The manner in which one end of the auxiliary tie link 70 is pivotally joined to arm 68 by a pivot pin 71, and the manner in which the other end of the auxiliary tie link is pivotally joined to lugs 72 on the key segment 10 by a pivot pin 73 is best seen in the broken-away portion of Fig. 2.

In a similar manner, each of the arms 49 of the spider 46 has a control yoke 75 and an auxiliary tie link 76, (Figs. 1 and 2), all pivotally assembled as described in connection with control yokes 53 and tie links 70. However, it will be seen by inspection of Fig. 2 that the control yokes

53 and control yokes 75 connect the key segments to larger segments located at opposite sides of the key segments. In other words, control yokes 53 bridge alternate bevelled joints 77 between segments, and the control yokes 75 bridge intermediate bevelled joints 78. This manner of assembly is relevant to the opposite rotation of the spiders 40 and 46 with respect to each other during collapse and expansion of the drum, as will be described in greater detail below.

For drums of larger size, I may provide more than one pair of rotatable collars or spiders 40 and 46 with associated connecting yokes, to give additional support to the larger segments.

To further guide the movement of the larger segments during the collapsing and expanding operation, a telescoping guide assembly is associated with each segment. Such assembly comprises a hollow cylinder 80 (Fig. 1) threaded at its base 81 into a suitably threaded radial hole 82 (Fig. 5) in the fixed collar 19. A cylindrical guide stud 83 (Figs. 1 and 2) is slidably disposed within the cylinder 80 and is threaded at its outer end 84 (Fig. 1) into a hole in larger segment 13. The interior of the hollow cylinder 80 is lined with suitable bearing metal 85.

To aid in maintaining the segments in proper relation when in the expanded position, each end of each key segment is provided on its inside face with a small arcuate stop member 88 fastened thereto by means of a screw 89.

In order to impart the desired profile to the rim of the tire being built on the drum, the circumferential edges of the smaller segments are provided with arcuate turned-over rims 90 of suitable form and the edges of the larger segment are likewise provided with similar rims 91. The rims are of the same arcuate length as the segments proper, and in no way interfere with expansion or collapse of the drum. The rims are constructed with an inner stepped portion 92 (Fig. 1) which fits into the similarly stepped edge of each segment, the outer surface 93 of the rim forming a continuous smooth building surface with the surface of the drum segment. Attaching screws 94 passing through the rim member into the segments at a convenient angle in the manner shown permit easy removal of the rim members for substitution of differently shaped rims as desired.

As shown in Fig. 7, suitably shaped spacer members 96 of various widths, each of the same arcuate length as the segment to which it is attached, may be interposed between the rims and the segments for the purpose of building tires of various sizes on the one drum. The spacers and rims are easily assembled with the segments by means of machine screws 97 passing through the spacers into the segments, and machine screws 98 passing through the rims into the spacers as shown.

Turning now to the details of the structure of the actuating plate 38 and the pneumatic actuating cylinder 18 associated therewith, it will be observed in Fig. 1 that three fixed axially extending stop bolts 100 (two being shown) pass slidably through holes 101 in the axially movable plate 38, and are threaded through cylinder head 47 into correspondingly threaded hole 102 in the end of hub portion 17. Bushings 103 of suitable bearing metal are disposed within the holes 101. Nuts 104 on the threaded portion of the bolts 100 maintain the cylinder head 47 in place along with studs 133 on the end of the hub portion 17. The inner face of the plate 38

is recessed as at 105 to provide clearance for the nuts 104.

When the drum is in collapsed condition, the heads 108 of the bolts 100 engage resilient washers or cushions 109 disposed within enlarged portions of the holes 101 in the actuating plate 38. Thus, the heads of the bolts form stops for the plate 38, as indicated most clearly in Fig. 3. The position of these stops may be adjusted by threading the bolts 100 into or out of the hub portion 17. An annular axially projecting resilient cushion 110 (Fig. 1) is disposed partly within a recess passing around the inner face of the actuating plate near the periphery thereof. This resilient cushion 110 engages the outer face of cylinder head 47 when the drum is in expanded position.

Disposed within the pneumatic actuating cylinder is a piston assembly 115 which is connected by a piston rod 116 to the actuating plate 38. The piston rod fits into a central recess 117 in the plate 38 and is fastened thereto by a bolt 118 passing through the front of the plate into the piston rod. A bolt 119 likewise secures the piston rod 116 to the piston assembly 115. The passage of the piston rod 116 through the cylinder head 47 is sealed against air leakage by a suitable packing ring 120, held in place by a cover plate 121 secured by screws 122 to the front of the cylinder head. Suitable packing 123 is also provided around the perimeter of the piston assembly 115.

The hub 16 has a central axial passageway 125 therethrough for introducing and removing compressed air from the pneumatic cylinder 18. A co-axial pipe 126 within the passage 125 is threaded into a cylinder head assembly 127 for introducing air during the collapsing stroke of the piston 115. During the drum expanding stroke (movement from left to right in the drawings) of the piston 115, the pipe 126 serves as an exhaust channel for the air, while air is introduced through axial passageway 125 in the hub, and thence through a passageway 128 drilled radially in the wall of hub portion 17, into a passage 129 drilled axially through the wall of hub portion 17, and finally into a passageway 130 drilled radially through the cylinder head 47, whence the air has access to the interior of the cylinder 18. The ends of the drilled passageways 128 and 130 are sealed off from the outside atmosphere by tap screws 131 and 132 respectively.

As the piston assembly 115 approaches the cylinder head 127 on the expanding stroke, a projecting portion 135 of the piston slides snugly into a central opening 136 in the cylinder head, thereby substantially sealing off said opening against further escape of the air in the cylinder. An additional passage 137 through the cylinder head has therein a one-way ball check valve assembly 138 which also prevents escape of air. There remains only a small passageway 139 containing a restricted metering orifice 140, available for the escape of the remaining air toward the end of the piston stroke. Consequently, the piston is slowed down and pneumatically cushioned to a gentle stop at the end of its stroke, preventing shock and strain on the various drum parts. It will be evident that this cushioning arrangement in no way decreases the positive pressure exerted on the piston at the start of the collapsing stroke, since the air introduced through pipe 126 has access to substantially the full area of the face of the piston through the central open-

ing 136, the passageway 139 and the passageway 137, which is made available by automatic opening of the ball check valve 138 upon application of air pressure.

5 In a similar manner, a central projection 142 on the other end of the piston 115, a ball check valve 143, and a metering passageway (not shown) in cylinder head assembly 47, cooperate to pneumatically cushion the piston at the end of the collapsing stroke.

For the purpose of rotating the drum during the tire building operation in the usual manner, the end of the hub 16 is detachably coupled to a shaft 150 of a conventional tire building machine (not shown) by means of a coupling assembly 151. This assembly includes, on the end of the hub 16 a central spider ring 152 having a core 153 into which is threaded for support the end of the central air pipe 126. A washer or gasket 154 on the opposing face of a similar central air pipe 155, suitably supported in the center of an axial air passage 156 within the machine shaft 150, forms an air-tight seal when the hub and shaft are drawn together. An outer resilient gasket 157 similarly seals the joint between the hub air passage 125 and the shaft air passage 156. It will be understood that the compressed air may be introduced into or removed from the pipe 155 and the passage 156 through the usual control valves and by the use of a conventional rotary seal coupling (not shown) conveniently located at the end of the shaft 150 extending from the opposite side of the tire building machine.

35 The central portion of the end of the machine shaft 150 has a projection 160 which seats in a corresponding center counterbore in the end of the hub 16. The projection 160 acts as a register for centering the hub 16 with respect to the shaft 150 in assembly.

40 For detachably securing the hub to the shaft there are provided within the coupling assembly 151 a plurality of axially extending studs 161. Each stud is securely threaded into the end of the hub 16 and is provided with a smooth cylindrical extension 162 which slides into a corresponding recess 163 in the machine shaft 150. One side of the cylindrical extension 162 has an arcuate "flat" 164 (Fig. 3), against which a radially extending eccentric 165 bears. The eccentric 165 is mounted in a recess 166 extending radially inwardly from the outer periphery of the shaft 150 in such manner that turning of the eccentric in a clockwise direction by means of a suitable wrench causes it to bear tightly against the arcuate flat 164 of the stud extension 162, thereby drawing the stud, and the hub 16, against the shaft 150 and effecting a positive lock between the hub and the shaft. To disengage the hub from the shaft, it is simply necessary to turn the eccentric 164 in a counter-clockwise direction, whereupon the stud 161 may be withdrawn freely from the recess 163 in the shaft 150.

65 The operation of the collapsing and expanding mechanism will now be described. After a tire has been built or assembled on the cylindrical surface of the expanded drum and it is desired to remove the tire therefrom for further operations, such as vacuum shaping and vulcanizing, the collapse of the drum is initiated by admitting air through central pipe 155 in the machine shaft 150 and central pipe 126 within the hub 16. This moves the piston 115 and the piston rod 116 from right to left as viewed in

Fig. 1, thereby moving the actuating plate 38 axially on the bolts 100. The pivotal arms 36 move axially with the plate 38, at the same time drawing the pivotal joint 35 between links 25 and 26 axially and radially, thereby collapsing the links 25 and 26 in a radially inward path lying in a plane parallel to the axis of the drum. As the toggle links 25 and 26 start to collapse, the key segments 10, 11, and 12 pivotally attached to links 26 by pivot pins 33 begin to move inwardly. The inward movement of the key segments is rectilinear and radial, without any axial or rotary component of motion.

The inward movement of the key segments 10, 11 and 12 causes, through the action of the pivotal auxiliary tie links 70, a tilting of the connecting yokes 53 about their fulcrums or pivot pins 55 in a counter-clockwise direction as viewed in Figs. 2 and 4. Such tilting of the yokes 53 is accompanied by clockwise rotation of the spider member 40 on which the yokes are pivotally mounted. Simultaneously, the connecting yokes 75 are tilted in a clockwise direction about their respective pivot pins, with consequent counter-clockwise rotation of the supporting spider 46.

The tilting of connecting yokes 53 and 75 initiates inward radial movement of the major segments 13, 14 and 15 pivotally joined thereto. As the key segments 10, 11 and 12 continue to move inward the larger segments 13, 14, and 15 continue to be drawn over them to a final collapsed position. At this time the actuating plate 38 engages the heads 108 of stop bolts 100, and the piston 115 engages the cylinder head 47 as shown in Fig. 3. The larger segments are guided or steadied in their inward radical movement by the telescoping studs 83 sliding within guide cylinders 80. The radial movement of the larger segments is also rectilinear, being without any axial or rotary component. In the collapsed position, as shown in Figs. 3 and 4, the yokes are folded compactly over the ends of the key segments and the larger segments are drawn in close proximity thereto in overlapping relation, to effect a high degree of collapse.

The expansion of the drum is the opposite of the foregoing operation. Application of air pressure to the passageway 156 in the machine shaft 150 and the passageway 125 in the hub 16 causes the piston 115 to move toward the cylinder head 127. This produces axial movement of the actuating plate 38 away from the heads of the stop bolts 100, and produces axial and outward radical movement of the arm 36, thereby initiating, through the pivotal links 25 and 26, outward movement of the key segments 10, 11 and 12. Movement of the key segments causes clockwise tilting of the yokes 53 about their pivot pins 55 with consequent counterclockwise rotation of the spider 40 with respect to the hub portion 17. Simultaneously the yokes 75 are tilted in a counter-clockwise direction and the supporting spider 46 likewise begins to revolve clockwise. Such tilting of the connecting yokes causes the larger segments 13, 14 and 15 to move outwardly radially until the stops 43 on the spiders 40 and 46 contact the stops 45 on the fixed collar 19. Outward movement of the key segments 10, 11 and 12 continues until the resilient cushion 110 on the inner face of the actuating plate 38 engages the cylinder head 47.

The pivotal joint or fulcrum 55 of the connecting yokes 53 is so located that the initial inward collapsing movement of the key segments does

not produce an immediate movement of the larger segments. This permits the key segments to clear the larger segments before inward movement of the latter is begun. Specifically, I locate the various stops, such as the stops 43 on the rotating spider member 40 and stops 45 on the fixed collar 19 in such manner that when the drum is in the expanded condition the center of the fulcrum pin 55 of the connecting yoke 53 has traveled a small distance over or beyond the center line drawn from the center of the drum through the center of the pivot pin 63 which joins the yoke to the larger segment. This distance beyond "center" position represents the extent to which the pivot 63 may move in response to movement by the key segments without producing inward movement of the larger segments. Such over-center placement of the pivot 55 provides, in effect, for "lost motion," or delay, in the inward movement of the larger segments so that the key segments are permitted to move clear of the larger segments and the latter are caused to follow the key segments without interference therewith. The pivots of all of the connecting yokes 53 and 75 are similarly disposed beyond their "center" positions when the drum is in the expanded position. The fact that the pivots are so placed also establishes a positive locking of the larger segments in proper position, since small movements of the pivots which might be caused by vibration or the shock of starting or stopping the drum do not tend to cause collapse of the segments.

In like manner, I dispose the center of pivot pin 35 joining the links 25 and 26, which collapse the key segments, beyond a center line drawn through the centers of pivot 33 to the key segment and pivot 28 to the fixed collar when the drum is expanded. This over-center positioning of the pivot pin 35 is effected when the resilient cushion 110 on the inner face of the actuating plate 38 engages the cylinder head 47. This produces a positive locking action on the key segments so that they do not tend to collapse upon small movements of the links 25 and 26.

On the expansion stroke the fulcrum pins of the connecting yokes, such as pins 55 of the yokes 53, arrive at their over-center position, as determined by engagement of the stops 43 and 45, before the pivot pins 35 of the collapsing links associated with the key segments arrived at their over-center position, as determined by engagement of the resilient cushion stop 110 on the actuating plate 38 with the cylinder head 47. Therefore, the larger segments are locked in the expanded position before the key segments have completed their expansion movement. This has the desirable effect that no collapsing motion of the larger segments can take place until after the fulcrumed yokes attached thereto have been moved away from over-center position by the key segments. Hence, locking of the key segments in position when the drum is expanded effects a locking of the entire drum. The drum is therefore exceptionally stable in the expanded position, particularly against centrifugal forces or rotary inertial forces occasioned by sudden starting, stopping, or reversing of the drum, since the key segments are collapsible only through an axially operable linkage.

From the foregoing, it is seen that I have provided a collapsible tire building drum in which the various peripheral segments, when the drum is expanded, are positioned in a positively locked position, such positioning being determined by

properly located stops, and being unaffected by any wear which might occur on various parts of the collapsing linkages.

Also, I have provided a drum in which the actuating mechanism operates essentially axially of the drum, and is therefore relatively unaffected by the rotation of the drum, so that expansion and collapse may be effected with equal ease while the drum is rotating in either direction or while the drum is stationary. Sudden starting or stopping of the drum does not tend to cause expansion or collapse.

I have disposed the various segments and collapsing members symmetrically with respect to the drum axis and with respect to the transverse center line of the drum, so that the parts are largely interchangeable. Thus, for example, if it becomes necessary to repair any one of the key segments, a single spare key segment will serve as a substitute for any of the key segments 10, 11 or 12. Therefore, it is possible to maintain a number of such drums in continuous operation with a minimum number of spare parts.

Because of the way individual rims are detachably mounted on the edges of each of the segments, tires with a variety of rim profiles may be constructed on the one drum by substituting rims of different contours. The rims in no way interfere with expansion or collapse of the drum, and they may be changed when the drum is in either the expanded or collapsed position, without removing the drum from the machine. In the same way, detachable spacers may be interposed between the rims and the segments to vary the width of the drum surface, while still retaining a smooth uninterrupted building surface. Equal sized spacers may be placed on each side of the drum, so that the symmetry and balance of the drum is not disturbed. Since the center line of the drum is not disturbed the usual adjacent auxiliary equipment remains in proper alignment with respect to the drum as the width thereof is changed by this method.

By locating the actuating means, such as a pneumatic cylinder, within the hub of the drum, I have provided a self-contained unit that can be easily attached to a conventional tire building machine. Various sizes of drums containing such internal actuating means can be attached conveniently to the tire building machine.

The various cushioning means associated with the collapsing structure, particularly the pneumatic cushioning means provided at each end of the stroke of the actuating piston, permit rapid expansion and collapse of the drum without shock or strain on the drum parts.

Having thus described my invention, what I claim and desire to protect by Letters Patent is:

1. A collapsible building drum comprising in combination a hub, a set of key segments, an actuating member connected between said hub and key segments for drawing said key segments radially inwardly, a set of intermediate segments, pivotal links joining said key segments to said intermediate segments for drawing said intermediate segments inwardly over said key segments, and collars pivoted to said links and mounted for limited rotation about said hub for controlling the motion of said intermediate segments.

2. A collapsible drum comprising a hub, a set of key segments and a set of larger segments alternately placed with respect to said key segments, a toggle linkage actuated axially of the drum secured only to the said key segments to

pull said key segments radially inwardly with respect to the hub in a rectilinear path, pivotal linkages connecting said key segments to said larger segments for drawing the larger segments inwardly radially over the key segments, said pivotal linkages being fulcrumed on spider members mounted for limited rotation about said hub.

3. A collapsible building drum comprising a hub, an actuating cylinder within said hub, a collapsing linkage actuated axially by said cylinder, a set of peripheral key drum segments mounted on said hub for inward and outward radial movement by said collapsing linkage, a set of peripheral larger drum segments pivotally connected to said key segments and movable inwardly or outwardly radially with movement of said key segments, and means for limiting the movement of said larger segments to movement in a direction purely radially of said hub.

4. A collapsible building drum comprising a hub, a set of key members and a set of larger members alternately placed with respect to said key members, collapsing means for each key member actuated axially of said hub and comprising a link, a pivotal joint connecting said link to said key member, a second link, a pivotal point connecting said second link to said hub, and a connecting pivotal joint joining the said two links; means for positioning the said connecting pivotal joint beyond a center line drawn between the said pivotal joint to the key member and the said pivotal joint to the hub when the drum is in the expanded position, whereby the key members are positively maintained in position, the said key members being pivotally linked to said larger members to draw the said larger members inwardly radially after the key members upon actuation of the said collapsing means and the pivotal links joining the key members to the larger members being linked to members mounted for rotation about the hub but immovable axially, whereby collapsing movement of the segments is limited to radial movement.

5. A drum comprising a central hub, a set of smaller sections and a set of larger sections alternately placed with respect to said smaller sections, an axially movable toggle linkage connected to said smaller sections for drawing said smaller sections inwardly to collapse the drum, and means for drawing said larger sections inwardly radially over said smaller sections comprising yokes connecting the larger sections to the smaller sections, each of said yokes being connected to one of said larger sections by a pivotal joint, and each yoke being connected by a pivotal fulcrum to a spider mounted for limited rotation about said hub, and stops on said spider for positioning the center of said pivotal fulcrum beyond a center line drawn between said pivotal joint and the said hub when the drum is in the expanded position, whereby the larger sections are positively maintained in position.

6. A building drum comprising a hub, a set of key members, a toggle linkage for collapsing said key members radially, means movable axially of said hub for actuating said toggle linkage, a stop on said hub contacting said actuating means when the drum is expanded for locating said toggle linkage in a positively locked position when the drum is expanded, a set of larger members, control yokes joining said larger members to said key members for radial movement over said key members upon collapsing the drum, guiding means for said control yokes, and stops contacting cooperating stops on said guiding means when

11

the drum is expanded for maintaining said larger members in a positively locked position when the drum is expanded.

7. A collapsible tire building drum comprising a hub, a set of key segments collapsible radially and a set of larger segments linked to said key segments for inward radial movement over said key segments, means for collapsing said key segments, each segment comprising a single body presenting a smooth outer working surface of definite width, the lateral edges of each segment having a stepped portion, a cooperating spacer piece having a corresponding stepped edge fitting into the lateral edge of each segment and forming a smooth continuation of the smooth working surface of such segment, the outer edge of the spacer piece being stepped similarly to the said stepped edge of the segment, a cooperating rim piece having a correspondingly stepped inner edge fitting into said outer edge of the spacer piece, means for detachably securing the spacer piece to the segment, and means for detachably securing the rim portion to the spacer piece.

8. A collapsible drum comprising a hub, a set of key segments collapsible radially, means actuated axially of said hub for collapsing said key segments, a set of larger segments alternately placed with respect to said key segments, means for drawing said larger segments inwardly radially over said smaller segments comprising connecting yokes pivotally connected to the larger segments and pivotally connected to the smaller segments, a collar for pivotally supporting and guiding said yokes, said collar being mounted for limited rotation about the said hub, and stops projecting from the hub for definitely locating said collar, when the drum is fully expanded, at a point such that the initial inward movement of the key segments in collapsing the drum produces motion of the said connecting yokes and rotatable collar without collapsing the larger segments, and continued inward movement of the key segments causes the larger segments to be drawn inwardly over the key segments in a path controlled by the said connecting yokes and rotatable collar.

9. A collapsible building drum comprising a hub, a set of key segments, a toggle linkage for collapsing and expanding said key segments radially, means actuated axially of the hub for operating said toggle linkage, a set of larger segments alternately disposed with respect to said key segments, means for actuating said larger segments comprising, rotatable spiders located at spaced points along said hub, fixed stops on the said hub cooperating with stops on said spider for limiting the rotation of said spiders, a plurality of connecting yokes pivotally mounted on said spiders, each yoke being pivotally joined to a key segment and pivotally joined to a larger segment adjacent said key segment so that inward movement of the key segment causes the larger segments to be drawn inwardly radially over the key segments by the pivotal connecting yokes, the pivoting of the connecting yokes being accompanied by rotation of the said rotatable spiders so that the path and extent of travel of the larger segments is thereby controlled, said rotatable spiders rotating in opposite directions with respect to each other during expansion and collapse of the drum, so that the said expansion and collapse is essentially uninfluenced by the rotation of the drum.

10. A building form comprising a hub, a set of key members, a toggle linkage connecting said

12

key members to said hub for collapsing and expanding said key members radially, a pneumatically actuated piston within said hub for operating said toggle linkage in a direction axially of said hub to collapse and expand the form, means for pneumatically cushioning said piston at each end of its stroke in operating said toggle linkage, a set of larger members alternately placed with respect to said key members, pivotal connecting links connecting said larger members to said key members for drawing said larger members inwardly after said key members in collapsing the form, and means for controlling the motion of said larger members including a member mounted for limited rotation about said hub and pivotally supporting said pivotal connecting links.

11. A building drum adapted to be expanded and collapsed comprising a hub, a set of arcuate key segments connected to said hub by a pivotal collapsing and expanding linkage, a set of arcuate larger segments connected to said key segments by a connecting pivotal collapsing and expanding linkage operable by movement of said key segments, said connecting linkage also being connected to guiding means supported on said hub, and said key segments and said larger segments forming a cylindrical building surface when the drum is in the expanded position, axially operable means for actuating said first mentioned linkage to expand and collapse said key segments, a stop associated with said hub engaging cooperating stops on said guiding means for said connecting linkage when the larger segments are in the expanded position, said stop being so located that the said pivotal connecting linkage controlling said larger segments is disposed in a positively locked over-center position when the larger segments are in the expanded position, and a stop associated with said hub engaging said actuating means when the key segments are in the expanded position, said stop being so located that the pivotal expanding linkage controlling the key segments is disposed in a positively locked over-center position when the key segments are in the expanded position, the relation of the said stops to the said guiding means and the said actuating means being such that on expanding the drum the stop controlling the position of guiding means for the larger segments is engaged by the guiding means before the stop controlling the position of the key segments is engaged by the actuating means for the key segments.

12. A collapsible building drum comprising in combination a hub, a first set of arcuate segments, axially operated toggle linkages for drawing said first segments inwardly toward said hub, further pivotal linkages between said hub and first segments movable radially but immovable axially whereby inward movement of said first segments is confined to purely radial movement, a further set of arcuate segments intermediate said first segments, said further pivotal linkages being pivotally attached to said intermediate segments to draw said intermediate segments inwardly with said first segments.

13. A collapsible building drum comprising in combination a hub, a first set of arcuate segments, a second set of intermediate arcuate segments, toggle linkages arranged in a plane parallel to the axis of the drum for collapsing movement in said plane, said toggle linkages being connected between said first segments and said hub, an axially movable member for collapsing said toggle linkages to draw the first segments

13

toward the hub, pivotal links between the second segments and the first segments to draw the second segments inwardly with the first segments, and pivotal links movable only in a plane transverse to the axis of the drum connected to said segments for restricting the collapsing movement of the segments to purely radial movement.

14. A collapsible building drum comprising in combination a hub, a first set of arcuate segments, a second set of intermediate arcuate segments, toggle linkages arranged in a plane parallel to the axis of the drum for collapsing movement in said plane, said toggle linkages being connected between said first segments and said hub, an axially movable member for collapsing said toggle linkages to draw the first segments toward the hub, pivotal links between the second segments and the first segments to draw the second segments inwardly with the first segments, further pivotal links movable only in a plane transverse to the axis of the drum con-

5 nected to said segments for restricting the collapsing movement of the segments and a radially telescoping guide fixed to the hub and to the segments for further steadyng and guiding the segments in a purely radial collapsing path.
